CLAIM

The ornamental design for a fragrance bottle, as shown and described.

DESCRIPTION

FIG. 1 is a top, front, right side perspective view of our new design for a fragrance bottle;

FIG. 2 is a front elevation view of the fragrance bottle shown in FIG. 1;

FIG. 3 is a right side elevation view of the fragrance bottle shown in FIG. 1, the left side being a mirror image thereof;

FIG. 4 is a rear elevation view of the fragrance bottle shown in FIG. 1;

FIG. 5 is a top plan view of the fragrance bottle shown in FIG. 1; and,

FIG. 6 is a bottom plan view of the fragrance bottle.

1 Claim, 2 Drawing Sheets
